UNITED STATES PATENT OFFICE.

BERNHARD DREYFUS, OF NEW YORK, N. Y.

DESIGN FOR A CURTAIN-LOOP.

SPECIFICATION forming part of Design No. 16,543, dated February 23, 1886

Application filed December 24, 1885. Serial No. 126,657. Term of patent 7 years.

To all whom it may concern:

Be it known that I, BERNHARD DREYFUS, a citizen of the United States, and a resident of New York, in the county of New York and State of New York, have invented a new and original Design for Curtain-Loops, of which the following is a specification.

In the accompanying drawing, forming a part of this specification, a perspective view of my design for curtain-loops is shown.

A represents loops of material having a furzy outer surface. B represent caps at the adjacent ends of the said loops. C represents a ball, bead, or like spherical object between the two caps B. D represent tufts on the outer ends of the loops A, and E represent cord loops at the said tufts. F represent cords on the ball or bead C.

The leading feature of my design consists of the two loops, the caps at the adjacent ends

of the same, and the spherical object between the said caps.

Having thus described my design, what I claim as new, and desire to secure by Letters Patent, is—

1. The design herein shown and described, the same consisting of two loops, caps at the adjacent ends of the same, a spherical object—such as bead or ball—between the caps, and of the cords F on said bead or ball, as set forth. 25

2. The design for curtain loops herein shown and described, the same consisting of two loops, caps at the adjacent ends of the same, a ball or bead between the said caps, tufts on the outer ends of the loops, and the cord loops E 35 at the said tufts, as set forth.

BERNHARD DREYFUS.
